(57) **CLAIM**

The ornamental design for a lamp holder, as shown and described.

DESCRIPTION

FIG. 1 is a perspective view of a lamp holder showing my new design;

FIG. 2 is a perspective view thereof from another angle;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is a perspective view thereof when the lamp holder is in use; and,

FIG. 10 is an enlarged view of portion 10 of FIG. 4.

The broken lines in the drawings illustrate portions of the lamp holder that form no part of the claimed design. The dot-dash broken lines in the drawings represent boundaries of the enlarged portion and form no part of the claimed design.
